(57) CLAIM

I claim the ornamental design for a canopy for a vehicle, truck, light delivery vehicle or similar vehicle, as shown and described.

DESCRIPTION

FIG. 1 is left side elevation view of a canopy for a vehicle, truck, light delivery vehicle or similar vehicle, showing my new design;

FIG. 2 is a right side elevation view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a rear perspective view thereof; and,

FIG. 8 is a front perspective view thereof.

1 Claim, 8 Drawing Sheets
